Inventor

Edward Tangye.

By his Attorney

Herbert W. Jenner.

UNITED STATES PATENT OFFICE.

EDWARD TANGYE, OF REDRUTH, COUNTY OF CORNWALL, ENGLAND.

METALLIC FUSE.

SPECIFICATION forming part of Letters Patent No. 364,318, dated June 7, 1887.

Application filed January 13, 1887. Serial No. 224,238. (No model.) Patented in England March 24, 1885, No. 3,774, and in France January 11, 1886, No. 173,458.

To all whom it may concern:

Be it known that I, EDWARD TANGYE, a citizen of Great Britain, residing at Redruth, in the county of Cornwall, England, have invented certain new and useful Improvements in Metallic Fuses and in the Method of Making the Same, (for which I have obtained patents in Great Britain, No. 3,774, bearing date March 24, 1885, and in France, No. 173,458, bearing date January 11, 1886,) of which the following is a specification.

My invention relates to improvements in the manufacture of safety damp-proof metallic fuse; and the objects of my improvements are, first, to reduce the thickness of the metal coating, and consequently the weight of the fuse to a minimum, and, secondly, to provide an article which shall be absolutely free from imperfections and perfectly damp-proof. I attain these objects by the use of mechanism illustrated in the accompanying drawings, in which—

Figure 1 is an end view, and Fig. 2 a front view, of the machine.

Similar letters refer to similar parts throughout.

A A represent rolls, which rest upon each other at the ends and are slightly apart where the grooves are cut and the guides fitted. They revolve in bearings B B', the latter being adjustable by the nuts C C. On the axles of these rolls gearing-wheels D D' are fixed.

E is a bed or base-plate upon which the screws F and G are fixed, and by means of which the bearings are adjusted by altering the position of the nuts C C. Upon the screws F the guide-plate H is secured, as shown, its exact position being regulated by the nuts I I. In this guide-plate dies J J are secured, of such a shape as to project to the center of the rolls, (terminating almost in a knife-edge.) They are held in position in the guide-plate by the screws K, and may be adjusted or removed. On the end of the base-plate a bracket, L, is secured, in which the axle M revolves. On one end of this axle the toothed wheel which gears into and drives the wheel D' is fixed, and on the other end the driving-pulley N is secured.

The machine is driven by a belt from any convenient motor.

In the rolls A A a graduated series of grooves,

a' a² a³ a⁴ a⁵ a⁶, is cut, as shown, alternating semi-elliptical and semicircular. The size of the hole formed by the grooves a' when the rolls are placed together depends upon the 55 size of the tube to be operated upon, and is arranged so that its longer diameter shall not be less than the diameter of the tube. The diameter of the hole formed by the grooves a² (or the longer diameter if the hole were oval) 60 is arranged so as not be less than the shorter diameter of the hole formed by the grooves a', and so on throughout the series.

The guide H is fitted with a die or dies, J, as shown, having holes to correspond in size 65 and shape with the holes formed by the grooves in the rolls, the largest, I', being circular to receive the tube as it comes to the machine, the second, I², being oval to receive the tube as it comes from the largest hole formed by the 70 grooves a' of the rolls which is oval, and the third, I³, being again circular to receive the tube as it comes from the second hole formed by the rolls which is circular, and so on oval and circular and gradually reducing in size throughout the series. In case of oval guide-holes the 75 longer diameter is placed vertically.

The rolls having been adjusted and being securely held in position, the machine is started by means of a belt on the pulley N and the 80 rolls revolve. The tube, which is previously filled with gunpowder or other suitable material dependent upon the use for which it is intended, and having its ends closed, is then passed into the largest circular guide-hole, is 85 caught by the rolls, and pulled through, being drawn into an oval shape, reduced in size, and increased in length. It is then returned to the next guide-hole, which is oval, passed in, and, being gripped by the rolls, is pulled through 90 and drawn into a circular shape again of smaller diameter and greater length. This process is continued until the desired size is reached. The last opening formed by the grooves a⁶ is so proportioned that by changing the sectional area of the tube from an elliptical to a circular form its capacity is increased. Thus in the case of tube to be used for fuse the contents are granulated and the rate and certainty of its action assured. By 95 this method I produce a lighter and more perfect tube than anything at present in use,

which may be covered, varnished, and countered, as desired.

I would not have it understood that I confine myself to the use of a single set of rolls, as here described, as I may use two or more sets.

I am aware that metal-coated fuses have been in use prior to this invention, and therefore do not claim the use of metal, broadly, as to a case for the powder; but

What I do claim as my invention, and desire to secure by Letters Patent, is—

1. The method of making metallic-coated fuse, which consists in first loading a short tube with gunpowder or other suitable material and closing the ends of it, and then passing the said loaded tube between two rolls having a series of meeting grooves, forming a gradually-reducing series of holes alternately circular and oval, which elongate and reduce the thickness of the said loaded tube, substantially as set forth.

2. The method of making metallic-coated fuse, which consists in first loading a short tube with gunpowder or other suitable mate-

rial and closing the ends of it, then passing the said loaded tube between two rolls having a series of meeting grooves, forming a gradually-reducing series of alternately circular and oval holes, which elongate and reduce the thickness of the said loaded tube, and finally passing the said tube through grooves which change its sectional form without elongating it, and thereby granulate its contents, substantially as set forth.

3. As an article of manufacture, a rolled fuse consisting of a core of inflammable material having a very thin inclosing metallic case formed about it, substantially as set forth.

4. As an article of manufacture, a rolled fuse consisting of a core of inflammable granulated material having a very thin inclosing metallic case formed about it, substantially as set forth.

In testimony whereof I affix my signature in presence of two witnesses.

EDWARD TANGYE.
